(57) **CLAIM**

The ornamental design for a cab for mining machine, as
shown and described.

DESCRIPTION

FIG. 1 is a perspective view of a cab showing our new
design.

FIG. 2 is a right side view of the cab shown in FIG. 1.

FIG. 3 is a left side view of the cab shown in FIG. 1.

FIG. 4 is a front view of the cab shown in FIG. 1.

FIG. 5 is a back view of the cab shown in FIG. 1.

FIG. 6 is a top view of the cab shown in FIG. 1; and,

FIG. 7 is a bottom view of the cab shown in FIG. 1.

The elements shown in broken lines are included for the
purpose of illustrating environment and form no part of the
claimed design.
